UNITED STATES PATENT OFFICE.

GEORGE D. BEASTON, OF PHILADELPHIA, PENNSYLVANIA.

SEPARATOR MECHANISM.

1,110,283.

Specification of Letters Patent.

Patented Sept. 8, 1914.

Application filed December 15, 1913. Serial No. 806,680.

To all whom it may concern:

Be it known that I, GEORGE D. BEASTON, a citizen of the United States, residing in the city of Philadelphia, county of Philadelphia, and State of Pennsylvania, have invented certain Improvements in Separator Mechanism, of which the following is a specification.

The primary purpose of my improved mechanism is to effect the expeditious and efficient separation of liquid from solid matter in the treatment of garbage, packing house by-products and the like, and in its preferred form the apparatus comprises a fluid actuated press having a cylinder provided with a fluid operated draining gate and a conical draining piston for separating liquid from solid matter, in combination with a tank adapted to discharge into the cylinder, means for carrying off from the cylinder liquid extracted from solid matter therein, and means for carrying off solids discharged from the cylinder by the piston when the gate is open.

In the accompanying drawings, Figure 1 is a part sectional elevation of apparatus embodying my invention; Fig. 2 is a vertical sectional view taken through the longitudinal axis of one of the presses; Fig. 3 is a sectional view taken on the line 3—3 of Fig. 2; Fig. 4 is a sectional view taken on the line 4—4 of Fig. 2, and Fig. 5 is a perspective view of a section of a press cylinder with the screen therein.

As illustrated in the drawings, the mechanism comprises a plurality of units each having a power cylinder 1 and work cylinder 2 mounted on supports 3, 4, and 5 which rest upon the respective foundation members 6, 7, and 8. Tanks 9 discharge through ducts 10, controlled by valves 11, to the respective cylinders 2, and the cylinders 2 discharge, under control of the respective imperforate head gates 14, to a channel 12 containing a conveyer 13.

Each cylinder 1 is provided with the heads 15 and contains a piston 16 fixed on a rod 17, which is adapted to reciprocate in the heads 15.

Each cylinder 2 has therein a perforated lining or screen 18, and a ram 19 which is fixed on the rod 17 and is movable thereby within the perforated lining 18. As each rod 17 bears constantly in heads 15, these heads act through the rods to hold the rams 19 in correct alinement and prevent their

bearing with undue force upon the interiors of the screens 18 and cylinders 2, particularly in the advanced positions of the pistons.

The ends of each cylinder 1 are connected by pipes 20 and 21 with a valve 22 which controls the communication of the respective pipes with an inlet pipe 23 and an exhaust pipe 24, whereby water is admitted to one end and exhausted from the other end of the cylinder to reciprocate the piston 16 therein and the piston 19 in the cylinder 2.

Upright cylinders 24' are fixed adjacent to the forward ends of the respective cylinders 2 and contain pistons 25 connected by rods 26 with yokes 27 on the respective gates 14; the gates being adapted to reciprocate in the vertical ways 28, being tapered downwardly to make a liquid tight engagement with the similarly tapered seats 28^a, and having tapered caps 14^a making liquid tight engagement with the similarly tapered flanges 2^a on the cylinders. The tops and bottoms of the respective cylinders 24' are connected by the pipes 29 and 30, through the valves 31, with inlet pipes 32 and exhaust pipes 33, whereby water is admitted to either end of the cylinders and simultaneously exhausted from the other end to open and close the gate.

Each cylinder 2 has therein, to carry off the liquid passed through the screen 18, the internal circular draining channels 34 which are intersected by the longitudinal bottom draining channel 35, the latter discharging through the branches 36 to a drain pipe 37.

Each ram 19 has a conical face 19^a containing draining channels 19^b which discharge through passages 19^c and 19^d to the cylinder 2 in the rear of the ram and each ram face is provided with a conical screen 38 for passing liquid from the mass in front of the ram to the discharge channels and passages. The conical or forwardly tapered ram penetrates the center of the mass subjected to pressure so as to effect a spreading and draining thereof, the center of such mass usually holding an excess of liquid due to the lack of proper provisions for extracting it.

Each gate 14 is provided with the internal screens 39, and with the internal draining channels 14^b intersected by a channel 14^c which communicates with a pipe 14^d, the latter discharging to a funnel 40 connected with the pipe 37.

In operation, the piston 16 and ram 19 of a unit are drawn back to the positions shown in Fig. 2 by exhausting water from the cylinder 1 through the pipe 20 and admitting water under pressure to such cylinder through the pipe 21. The valve 11 is then opened and solid and liquid matters are delivered from the tank 9 through the duct 10 to the cylinder 2 in front of the ram 19, the gate 14 being in position to close the forward end of such cylinder. When the cylinder 2 has received its charge, water is exhausted from the cylinder 1 through the pipe 21 and water under pressure is admitted to the cylinder through the pipe 20 to advance the piston 16 and ram 19, the latter squeezing the solid matter in the cylinder 2 so as to effectually express therefrom the liquid matter, which latter flows through the screens 18, 38 and 39 and is carried off by the several channels and passages to the pipe 37. The liquid having been expressed from the solid matter, water is exhausted from the cylinders 24' through 25 the pipes 29 and water under pressure is admitted to these cylinders through the pipes 30 to lift the pistons 25 which act through the rods 26 and yoke 27 to open the gate 14. The ram 19 is then moved forward to discharge the solid matter from the cylinder 2 to the channel 12 and onto the conveyer 13, by which it is carried away. The contents of the cylinder 2 having been discharged, water is exhausted from the cylinders 24' through 35 the pipes 30 and admitted through the pipes 29 to move the pistons 25 and close the gate 14, and the piston 16 and ram 19 are withdrawn to position for pressing the succeeding charge, as previously described.

Having described my invention, I claim:

1. In apparatus of the character described, a press cylinder having an imperforate head gate provided with drainage means, a ram provided with drainage means, and means for reciprocating said ram in said cylinder.
2. In apparatus of the character described, a press cylinder having an imperforate head gate provided with drainage channels, a ram having a forwardly projecting tapered part, and means for reciprocating said ram in said cylinder.
3. In apparatus of the character described, a press cylinder having drainage means, a reciprocating imperforate head gate for said cylinder, said gate having drainage means,

a ram having a forwardly projecting conical part, said ram having drainage means, and means for reciprocating said ram in said cylinder.

4. In apparatus of the character described, a cylinder provided adjacent to an end thereof with wedge shaped ways on opposite sides of said end, a wedge shaped seat at the bottom of said end and a wedge shaped member at the top of said end, in combination with an end gate having wedge shaped guides movable in said wedge shaped ways, a wedge shaped bottom part movable in said seat, and a wedge shaped top part adapted to fit said wedge shaped member. 60

5. In apparatus of the character described, a ram cylinder having drainage means, an imperforate head gate for said cylinder and having drainage means, a ram in said cylinder and having drainage means, a power cylinder having heads at opposite ends thereof, a piston adapted to reciprocate in said power cylinder, and a piston rod bearing in said heads and connecting said piston and ram. 70

6. In apparatus of the character described, a cylinder containing circular channels and a longitudinal bottom channel intersecting said circular channels and having one or more outlets, a cylindrical screen within said cylinder, an imperforate head gate for said cylinder and having drainage means, and a ram adapted to reciprocate within said screen and having drainage means. 85

7. In apparatus of the character described, a cylinder having drainage means, a head gate for said cylinder, said head gate having circular channels and a channel intersecting them, a screen supported by said head gate and extending over said channels, and a ram adapted to reciprocate in said cylinder. 90

8. In apparatus of the character described, a cylinder, in combination with a ram having a forwardly projecting tapered part 100 containing drainage channels and a screen supported by said ram and extending over said channels.

In testimony whereof I have hereunto set my hand this 11th day of December, 1913, 105 in the presence of the subscribing witnesses.

GEORGE D. BEASTON.
